United States Patent Office.

GEORGE W. BILLINGS, OF CHICAGO, ILLINOIS.

Letters Patent No. 97,752, dated December 14, 1869; antedated December 4, 1869.

IMPROVEMENT IN ELASTIC WASHERS FOR CARRIAGES, &c.

The Schedule referred to in these Letters Patent and making part of the same.

To all whom it may concern:

Be it known that I, GEORGE W. BILLINGS, of Chicago, in the county of Cook, and State of Illinois, have invented certain new and useful Improvements in Elastic Washers for Carriages, &c.; and I do hereby declare that the following is a full and complete description of the same, reference being had to the accompanying drawings, making part of this specification, in which—

Figure 1 is an outside view of the washer.

Figure 2, a view of the inside.

Figure 3, a transverse section.

Figure 4 is also a transverse section, with elastic filling.

Figure 5, a detached view of the elastic filling.

Like letters of reference refer to like parts in the different views.

The nature of this invention relates to a metallic elastic washer, the same being applied between a nut operated upon a bolt, and a plate of iron or wood, or between any two substances where elasticity is required, in consequence of the contraction and expansion or jarring of the bolt, whereby the plates, &c., are bolted together.

This washer is constructed of a circular plate of steel or other appropriate metal, A, fig. 1, rolled or hammered to the proper thickness that the size and use of the washer may require.

In the centre is punched a hole, of a size proper for the admission of the bolt. The plate is then struck up with dies or punches into a concavo-convex shape, as shown in fig. 3, which represents a cross-section of the washer.

On the edge of the concave side is formed a continuous rim, B, by turning inwardly the edge of the plate, forming thereby a strong, hoop-like band, of sufficient

depth and strength to resist the pressure which may be exerted upon the crown of the washer on screwing up the nut, thereby preventing the washer from spreading and becoming flattened.

By giving the washer this concavo-convex shape and rim, and making it of steel properly tempered, a strength and elasticity of character are obtained that will adapt it to the contraction and expansion of the bolt, subject to changes of temperature, thereby keeping the plates of iron, wood, or other material, closely and firmly in contact.

In order to add to the elasticity of the washer, the concave is fitted with an elastic filling, C, fig. 4, which may be of rubber or felt, of hair or wood. This filling should be made full, and projecting beyond the rim, so that on the application of pressure, the concave surface will be thoroughly filled with the elastic material.

By this addition to the washer, it becomes more elastic, and well adapted to rail-joints, car-trucks, wagons, harvesters, or any place where a continuous jarring is liable to loosen an ordinary nut upon a bolt.

What I claim as my invention, and desire to secure by Letters Patent, is—

1. A metallic concavo-convex washer, so constructed that the edge of the concave side shall have a continuous rib or rim, B, substantially as described, and for the purpose set forth.
2. The combination of the concavo-convex washer, A, rim B, and filling C, in the manner as and for the purpose described.

GEO. W. BILLINGS.
